UNITED STATES PATENT OFFICE.

JOHN H. McCORMICK, OF CRESTON, IOWA.

MOTOR-SUPPORT.

1,397,433.

Specification of Letters Patent.

Patented Nov. 15, 1921.

Application filed October 7, 1920. Serial No. 415,326.

To all whom it may concern:

Be it known that I, JOHN H. McCORMICK, a citizen of the United States, residing at Creston, in the county of Union and State of Iowa, have invented certain new and useful Improvements in Motor-Supports; and I do declare the following to be a full, clear, and exact description of the invention, such as will enable others skilled in the art to which

10 it appertains to make and use the same.

This invention relates to an improved motor support for use in connection with a motor in which one or both of the usual supporting brackets have become broken, the 15 support being so constructed that it may be put in place either before or after the brackets have become broken.

Another object of the invention is to so construct the support that it will have a 20 close fit with the motor and also have a close engagement with the lower portion of the motor bracket and have such engagement with this bracket that it will be prevented from having sliding movement when 25 in use.

Another object of the invention is to so construct this support that it follows closely the contour of the motor casing and hanger bracket and thus prevents danger of a hole 30 being worn in the motor casing.

Another object of the invention is to so construct this support that it may be easily and quickly put in place and further so constructed that it will be firmly held in 35 place and prevented from accidentally slipping loose.

Another object of the invention is to so construct this support that it may be put in place before the hanger brackets have become 40 broken and serve as means for preventing vibration of the engine and thus prevent breaking of the hanger brackets.

This invention is illustrated in the accompanying drawings, wherein:

45 Figure 1 is a bottom plan view showing the support applied to a motor.

Fig. 2 is a transverse sectional view taken along the line 2—2 of Fig. 1.

50 Fig. 3 is an enlarged view showing the motor hanger brackets and the outer portion of one of the hanger bars in place.

Fig. 4 is a perspective view of one of the hanger bars.

55 This improved motor support is used in connection with a motor 1 which is of a conventional construction and suspended from

the chassis bars 2 by hanger brackets 3 which are also of a conventional construction and provided with usual side flanges 4 and center web 5. This center web or finger 5 extends longitudinally of the bracket to a point intermediate the length of the bracket where the bracket is bent transversely so that the bracket will extend from beneath the securing flanges 6 of the motor casing 65 to a point above the flanges for engagement with the chassis bars 2. It will thus be seen that pockets 7 will be provided upon the sides of the finger 5 between the finger and the side flanges 4 of the bracket. It has been 70 found that vibration of the motor will often cause these hanger brackets to break off and it is then necessary to weld a new bracket in place or provide a supporting yoke for the motor. Supports for this purpose have 75 been provided but it has been found that the supports now in use do not have a close fit with the motor and hanger brackets and therefore the motor is permitted to vibrate and this causes the supporting yoke to wear 80 openings in the crank casing of the motor.

The device which will now be described is however so constructed that it has a close fit with the motor and hanger brackets and is prevented from having longitudinal or transverse movement and therefore will securely hold the motor and prevent vibration. Therefore, the device will serve very efficiently to support a motor in which the hanger bracket has broken and further may 90 be used before the brackets have broken and will serve to prevent vibration and thus prevent breaking of the brackets.

This support is in the form of hanger bars 8 each of which is constructed as shown 95 in Fig. 4. The hanger bar is provided with a foot 9 at its inner end which is provided with openings 10 to receive the securing bolts 11 by means of which the two hanger bars will be securely clamped beneath the motor. 100 This hanger bar is provided at its outer end with spaced fingers 12 having hooked end portions and thus constituting hooks which will engage the chassis bar as shown in Fig. 2 and as shown in Fig. 3 will extend longitudinally of the pocket 7 between the finger 5 and the flanges 4 of the brackets 3. At the base of the hooks, the hanger bar is bent to offset the hooks and permit the hanger bar to engage the lower portion of the hanger 110 bracket beneath the flanges 6 of the motor. This further provides an abutment shoulder

13 which will engage the brackets beneath the flanges of the motor and serve to prevent movement of the hanger bar longitudinally in one direction. The hanger bar is again 5 bent longitudinally at the lower end of the bracket to bring the hanger bar into engagement with the base of the crank case and from this point to the foot 9, the hanger bar is curved longitudinally so that it con- 10 forms to the contour of the crank casing. It will thus be seen that when the support is put in place, it will conform to the contour of the crank casing and hanger bracket and will be held against longitudinal move- 15 ment by the shoulders 13 and 14 and against transverse movement by the hooks 12 which fit into the pocket 7. Vibration of the motor will therefore be overcome and breakage of the brackets prevented or very efficient sup- 20 porting of the motor permitted in case the support is put in place after breaking of a bracket.

I claim:

1. A motor support comprising hanger 25 bars for extending transversely beneath a motor from opposite sides thereof, each of

said hanger bars having a head at its inner end and spaced hooks at its outer end for fitting between the side flanges and center web of a motor supporting bracket, the arm 30 being bent transversely adjacent the inner ends of the hooks to offset the hooks from the body of the bar and the bar being again bent transversely in spaced relation to the hooks and curved longitudinally throughout the 35 remainder of its length, and draw bolts passing through openings in the heads at the inner ends of said bars.

2. A motor support comprising hanger 40 bars each having a fastener receiving foot at its inner end and spaced chassis bar en- 45 gaging hooks at its outer end, the hanger bar being bent transversely adjacent the hooks to offset the hooks and again bent transversely in spaced relation to the hooks and curved longitudinally from the second 45 bend to said foot, and fastener means ad- justably connecting the feet of the base.

In testimony whereof I have hereunto set my hand.

JOHN H. McCORMICK.
